COIN OPERATED SHOPPING BAG SALES RACK
OR SIMILAR ARTICLE

Raymond M. Terry, 5560 Ascot Drive, Oakland, Calif.

Filed Oct. 20, 1959, Ser. No. 57,985

Term of patent 14 years

(Cl. D52—3)

Figure 1 is a perspective view of a coin operated shopping bag sales rack or similar article, showing the front and left side, embodying my new design; and

I claim:

The ornamental design for a coin operated shopping bag sales rack or similar article, as shown.
